UNITED STATES PATENT OFFICE

157,921

PLASTIC FILM MATERIAL

Michael Angelo Susi, New York, N. Y., assignor to Toscony Fabrics Inc., New York, N. Y., a corporation of New York

Application June 14, 1949, Serial No. 3,252

Term of patent 3½ years

(Cl. D92—1)

To all whom it may concern:

Be it known that I, Michael A. Susi, a citizen of the United States, residing in the city of New York, county of New York, and State of New York, have invented a new, original, and ornamental Design for a Plastic Film Material, of which the following is a specification, reference being had to the accompanying drawing, forming a part thereof.

The figure of the drawing is a plan view of a plastic film material, showing my new design.

The broken lines outline a design unit which is repeated over the fabric in regular succession as indicated.

I claim:

The ornamental design for a plastic film material, as shown and described.

MICHAEL ANGELO SUSI.
